UNITED STATES PATENT OFFICE.

DENNIS FRANK STANLEY, OF BOZEMAN, MONTANA.

TABULATING DEVICE.

1,270,892.

Specification of Letters Patent.

Patented July 2, 1918.

Application filed August 20, 1917. Serial No. 187,160.

To all whom it may concern:

Be it known that I, DENNIS F. STANLEY, a citizen of the United States, residing at Bozeman, in the county of Gallatin and State of Montana, have invented certain new and useful Improvements in Tabulating Devices, of which the following is a specification.

The present invention relates to improvements in tabulating devices, especially adapted for use in connection with typewriting machines, and other machines which utilize a tabulating apparatus as a part of the machine.

15 The primary object of the invention is the provision of means readily accessible to the operator and designed for setting the tabulator stop singly or one at the time, or for clearing all of the tabulator stops simultaneously. The invention involves the utilization of a device which is simple both in construction and operation, is durable, compactly arranged, and applicable without alteration to the typewriter, to most all standard machines now in use employing the customary notched tabulating rack bars.

The invention consists in certain novel combinations and arrangements of stops, and means for operating these stops to either set them or clear them, as will be hereinafter more fully described and claimed.

In the accompanying drawings I have
illustrated my invention adapted for use in
connection with a typewriter of standard
make, this physical embodiment of the in-
vention being made according to the best
modes I have so far devised for the practical
application of the principles of my inven-
tion. While I have illustrated the device
adapted for use on a typewriting machine,
it will be understood that the device is
equally applicable to other machines, and I
contemplate such use of the tabulating de-
vice.

45 Figure 1 is a side elevation of so much of a well-known type of typewriter as is necessary to illustrate my invention in connection therewith.

Fig. 2 is a rear elevation of the machine 50 of Fig. 1.

Fig. 4 is a perspective view of a crank.

55 Fig. 5 is an enlarged detail edge view of

the tabulating rack bar showing the relation of a stop thereto.

Fig. 6 is a side elevation of one of the stops.

Fig. 7 is a perspective view showing one end of the tabulating rack bar, and two stops thereon.

In the preferred embodiment of the invention as illustrated in the drawings, I have indicated the typewriting machine frame by 1, and the typewriter is equipped with keys as indicated at 2, and at the rear the customary rack bar 3 is indicated, which extends across the rear upper edge of the typewriting machine, and in connection with this rack bar I employ a number of stops 4, and there are as many stops, as there are notches 3' in the tabulator rack bar 3. Thus, it is possible, by sliding the typewriter carriage along the typewriter frame in usual manner, to bring any desired notch with its stop in position to be acted on by the operating parts of my invention, either to set the stop in position, or to clear the stop, i. e. to move the stop into inoperative position. 70 75 80

The stop 4 is fashioned with a tooth 5, and it also has a short hook 6, the latter adapted to engage the flange 7 of the hinged plate 8, and the tooth 5 is adapted to engage the notch 3' of the rack bar. On the top of the stop is attached a flat spring 9 having a bent locking end 10 which is adapted to coact with the locking plate 11. This locking plate is an angle iron secured at 12 to a fixed portion of the frame of the typewriter, and extends parallel with the rack bar of the typewriter. The hinged plate 8 is located just beneath the rack bar, and beneath this hinged plate is the clearing bail 12', which is pivoted at 13, and has its flange 14 extending across the rear of the machine, free of the rack bar, and in position to engage the tooth 5 of the stop 4. This clearing bail is adapted

to be moved so that it will engage one or 100 more of the stops that have been set, and lift them to inoperative positions. Thus, in Fig. 5 it will be seen that the stop 4 has been lifted by the action of the flange 14 of the bail 12, and the hooked end or locking end 105 10 of the spring 9 has been sprung over the flange 11 of the locking plate, and the stop will remain held in this position, even after the locking bail falls to the dotted position of Fig. 5. The stop is held in this 100

position by means of the hook 6 and the hook 10 of the spring.

The stop is set in operative position by direct action thereon, and it is moved to 5 clear position indirectly through the interposition of the clearing bail. For operating these two elements, the stop and the bail, I have devised the attachment to be described. The attachment utilizes a main bracket 15, 10 which is secured by screws to the typewriter frame at the lower rear portion thereof, and an upper bracket 16 located above the bracket 15, and in position to support the operating parts of the device. 15 A key lever 17 is located at one end of the typewriter, and extends along from rear to front within the frame, and has a key 18 thereon in convenient position for the operator, projecting out near the keyboard of 20 the typewriter. This lever is pivoted at 19 to the bracket 15, and its slotted end 20 is attached to the lever arm 21 by means of the screw 22, and the bent end 23 of this arm, is perforated to receive a crank 24. The 25 crank bar or rod is secured in the arm by means of a lock bolt or screw 25, and the crank rod or bar is journaled in the bracket 15 so that it can be oscillated in this bracket. The crank has a bent end 26, and 30 this end or arm 26 of the crank bar is adapted to operate the vertically reciprocable arm 27 by engagement of the crank arm 26 in the notch 28 of the arm. The joint between the bifurcated end 20 of the lever, and the 35 lever arm 21 is loose, the lever arm 21 is fixed on the crank bar 24, and the engagement of the crank arm with the notched vertical arm 27 is loose. A spring 29 engages under the lower end of the crank 40 arm 26, and tends to lift it, and it will be seen that by pressing down on the key 18, the crank arm 26 will turn down the arm 27, and by lifting the key 18, the crank arm 26 will lift the arm 27. The arm 27 is provided 45 with a slot 30 at its lower end, and this slotted end of the arm is guided in its movements by the bracket 15, which is straddled by this slotted end of the arm. Near its upper end the arm is slotted at 31, and a screw 32 in the bracket 16 serves to guide the arm in its movement, the lug 33 of the bracket also assisting in guiding the arm. At its upper end this arm is formed with an offset outwardly projecting finger 34 which 50 I shall call the depressing finger, and just beneath this finger but spaced therefrom is an elevating finger 35, and in Fig. 3 the utility of these fingers will be plainly evident. Thus by depressing the key 18, the 55 arm 27 will be lowered and the depressing

finger 34 will strike the stop 4 and lower it into the desired notch 3' of the rack bar. Lifting the key lever 17 will cause the elevating finger 35 of the arm to engage the clearing bail and lift the stops to inoperative position. 65

In this manner it will be seen that the tabulating device may be operated with facility and that a tabulating stop may be quickly set in the desired notch on the rack 70 bar for tabulating work.

Having thus described the invention, what is claimed herein, is:

1. The combination in a tabulating device with a rack bar and a stop, of a hinge plate 75 and a hook on the stop to pivotally engage said plate, a locking plate, and means on the stop to engage said locking plate, and means for lifting the stop to inoperative position, or lowering the stop to operative position. 80

2. The combination with a rack bar, a locking plate, and a hinge plate, of a stop having a tooth to engage the rack bar, a hook to pivotally engage the hinge plate, and a spring on the stop having a hooked end to 85 engage the locking plate, and a clearing bail pivoted in position, and means for moving said bail, to co-act with the stop, to move the latter to inoperative position.

3. The combination in a tabulating device 90 with a rack bar, a hinge plate, and a movable stop having a hook hinged on the hinge plate, of a vertically movable arm and means for moving said arm, and means on the arm in operative position to raise or depress the 95 stop.

4. The combination in a tabulating device with a rack bar and a hinge plate, of a stop pivoted on the hinge plate and a pivoted 100 clearing bail, a vertically movable arm having means to engage said stop and said clearing bail, and means for operating said movable arm as described.

5. The combination in a tabulating device with a rack bar, a hinged stop and a pivoted 105 clearing device, of a reciprocable arm having a pair of spaced fingers to engage the stop and clearing device respectively, and means for operating said arm as described.

6. The combination in a tabulating device with a rack bar, a movable stop and a pivoted clearing bail, of a vertically movable arm having a pair of spaced fingers adapted to engage the stop and clearing bail respectively, an operating lever, a crank bar, 110 and a crank arm engaging said movable arm for the purpose described.

In testimony whereof I affix my signature.

DENNIS FRANK STANLEY.
